UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR AN EYELET.

SPECIFICATION forming part of Design No. 25,833, dated July 28, 1896.

Application filed November 13, 1895. Serial No. 568,859. Term of patent 14 years.

To all whom it may concern:

Be it known that I, ELEAZER KEMPSHALL, of Newton, in the county of Middlesex and State of Massachusetts, have invented and 5 produced a new and original Design for Eyelets, of which the following is a specification.

This invention relates to a new and original design for an eyelet; and it consists in the novel features of shape and configuration 10 hereinafter fully described, and particularly claimed, and clearly illustrated in the drawings.

Reference is to be had to the accompanying sheet of drawings, forming a part of this application, wherein like characters are used to 15 indicate like parts wherever they occur.

Figure 1 is a perspective view showing my design. Fig. 2 is a longitudinal sectional view thereof.

20 The essential feature of my design consists in a tubular-shaped body having an overhanging flange that is concavo-convex in

cross-section, the edge of the flange being formed with projecting members.

a represents a tubular-shaped body, terminating at one end in an overhanging flange *a'*, whose edge is formed with projections *a²*. The flange portion of the eyelet, as shown, is concavo-convex in cross-section, with the projections on the flange extending toward the 25 30 end of the tubular body that is not provided with a flange.

I claim—

The design for an eyelet, substantially as shown and described. 35

In testimony whereof I have signed my name to this specification, in the presence of two subscribing witnesses, this 5th day of November, A. D. 1895.

ELEAZER KEMPSHALL.

Witnesses:

A. D. HARRISON,
ROLLIN ABELL.
